UNITED STATES PATENT OFFICE.

EDWIN A. ROBBINS, OF BOSTON, MASSACHUSETTS.

PIPE-WRENCH.

SPECIFICATION forming part of Letters Patent No. 269,234, dated December 19, 1882.

Application filed October 2, 1882. (No model.)

To all whom it may concern:

Be it known that I, EDWIN A. ROBBINS, of Boston, in the county of Suffolk and State of Massachusetts, have invented certain new and 5 useful Improvements in Pipe-Wrenches, of which the following is a specification.

The object of my invention is to provide a cheap, simple, convenient, and durable pipe-wrench, which shall overcome the objections 10 to those heretofore constructed; and it consists in the construction, combination, and arrangement of the several parts of the wrench, as hereinafter more fully described and set forth in the claims.

15 Figure 1 represents a perspective view of a pipe-wrench constructed according to my invention. Fig. 2 represents a side elevation of the same, with the jaws and handle in position to be applied to a piece of pipe. Fig. 3 20 represents a sectional elevation of the same, showing position of jaws and handle when power is applied thereto.

A represents the handle of the wrench, secured to the rear end of the lever-bar B, the 25 opposite end of which is pivoted to the fore part or bar C by a fulcrum-pin, D, passing through the same, the said bar C being provided with a housing, E, at its rear jointed end and a serrated jaw, F, at its opposite or 30 forward end.

H represents the adjustable jaw, provided 35 with a housing, K, which fits upon the bar C of the fore part, and from the rear part of the serrated adjustable jaw C extends a screw-threaded shank, L, which is provided with an adjusting screw-threaded nut, P, having a circumferential groove, R, within which fits the hook S, formed on the forward end of the said lever-bar B, and very nearly opposite the fulcrum-pin D, which pivots the lever-bar B to the said jaw-bar C, whereby great power is brought to bear upon the adjusting-nut P, so as to force the adjustable 40 jaw H against the pipe, about which the jaws F H are placed when the handle is in the position shown in Fig. 2. Now, power being given the handle A in the proper or forward direction, the serrations or teeth upon the inner faces of the said jaws are forced into the 45 surface of the pipe about being turned until

the said adjusting-nut P is brought against the face of the shoulder T, formed upon the joint end of the pivoted bar C near its housing K, and the bevel N of the handle lever-bar B against the corresponding bevel V, 55 formed upon the rear end portion of the pivoted bar C, and the said lever-bar B against the screw-threaded portion L of the said shank of the adjustable jaw H, all of which parts come together at the same time, so as 60 to form a rigid stop, whereby the said jaws are prevented from approaching each other; or, rather, the adjustable jaw at this point comes to a fixed stop, as shown in Fig. 3, so as to prevent injury to the pipe, as would frequently result were not stop provisions made, but the adjustable jaw permitted to force itself or to be forced toward the stationary jaw by the power exerted thereon (as in pipe-wrenches heretofore) until the pipe is crushed. 65 This construction also allows or causes the adjustable jaw to recede when the handle is brought back into the position shown in Fig. 2, thus relieving the hold of the teeth of the jaws upon the pipe expeditiously. Thus the 70 jaws are caused to hold with sufficient grip to turn the pipe, and are prevented from injuring the same by undue pressure thereon.

It will be seen in Fig. 3 that the pivoted lever-bar B has a shoulder, U, adjoining or 75 near its hook S, which contacts with the rear face of the said adjusting-nut P, so as to force the same forward, thus carrying the adjustable jaw toward the other, and that the said hook S is more especially designed to 80 draw the said nut and jaw back or in the opposite direction.

The essential features of my invention consist of the pivoted lever-bar and adjusting-nut, of the the novel construction whereby 85 the grip is governed or predetermined by the movement of the adjustable jaw and rigid stops above described.

Having thus described my invention, I claim—

1. The combination, with the stationary jaw F, having bar C, adjustable jaw H, having screw-threaded shank L, and adjusting-nut P, of the fulcrumed lever-handle connected with the periphery of the said adjusting-nut, 95 100

so as to actuate the said adjustable jaw toward and from the stationary jaw by movement of said handle, substantially as described, as and for the purposes set forth.

5 2. The combination, with the stationary jaw F, bar C, adjustable jaw H, shank L, and adjusting-nut P, of the fulcrumed lever-bar B,

provided with the hook S and shoulder U, and stops, substantially as described, as and for the purposes set forth.

EDWIN A. ROBBINS.
